WATER-EXCLUDING DOOR STRIP

Bernard A. Weyl and Kenneth N. Gahagan,
Pittsburgh, Pa.

Application July 22, 1953, Serial No. 369,544

5 Claims. (Cl. 189—46)

This invention relates to auxiliary doors, such as storm and screen doors, jalousies, and the like, that are mounted in doorways outside of the usual main doors.

In the use of such an auxiliary door, there is a tendency for rain to penetrate the seam or crevice between the top edge of the door and the frame of the doorway, with the effect that water drains downwardly upon the inside surface of the door and accumulates upon the sill between the main and auxiliary doors. Efforts have been made to overcome these objectionable incidents to the otherwise desirable use of auxiliary doors, such as the provision of weather-strips, or the grooving of the top and side edges of the doors to catch and drain away the rain penetrating the seam at the top of the door. None of the expedients to this end is without handicap. Weather-strips are, manifestly, unsightly and troublesome, while the presence of grooves in the top and side edges of a door spoils the appearance of the door edges, and, in the case of aluminum doors, with which this invention is particularly if not essentially concerned, the grooved edges are relatively sharp and dangerous to the fingers of the person using the door, especially if the fingers become caught or pinched between the edge of the door and the frame of the doorway.

In the use of auxiliary doors whose frames or bodies are constructed of aluminum, it is obviously impossible for the body of a door to be planed along its edges in such manner as a carpenter usually planes the edges of a wood-framed screen door, nicely to fit it in the doorway. Due to this circumstance, the art has turned to the use of extruded aluminum Z strips that are secured to the top and the two jambs of the doorway. The Z strips may be adjusted in their positions in the vertical plane of the frame of the doorway, whereby, when the strips have been properly adjusted and secured to the said frame, a seat of exactly the proper size is formed for the door. It is to be noted, however, that the use of Z strips does not prevent the penetration of rain in the objectionable manner alluded to, and as mentioned the practice has been to provide grooves in the edges of the door.

In accordance with the objects of this invention, the undesirable and objectionable use of grooved edges in aluminum doors is eliminated, and the infiltration of rain at the top of the door is prevented, by virtue of certain new and useful improvements in the structure of extruded metal Z strips used in mounting the doors.

The invention will be understood upon reference to the accompanying drawing, in which:

Fig. 1 is a view in front elevation of an auxiliary door, mounted with the structure of the invention in a doorway of a building which is fragmentarily illustrated;

Fig. 2 is a fragmentary view, illustrating to larger scale the upper right-hand corner of a Z strip assembly embodying the invention;

Fig. 3 is a sectional view, taken on the line III—III of Fig. 1, and showing the top of the frame of the doorway, with a Z strip structure of this invention secured

2

in service position, the scale of Fig. 3 being the same as that of Fig. 2;

Fig. 4 is a view in perspective, showing to still larger scale the upper right-hand corner of the Z strip assembly, 5 the line of sight of the view being indicated generally by the arrow in Fig. 2; and

Fig. 5 is a view comparable with Fig. 4, but with the two sections of the assembled Z strips moved apart, better to show the detailed structure of each section.

10 Referring to the drawings the frame of a doorway is shown in Fig. 1, and in this doorway an auxiliary door 3 is mounted. The frame 4 of the auxiliary door may be formed of extruded aluminum sections of conventional form, and the seat for the door is formed of Z strips 2, 2 secured to the two jambs 5, 5 of the frame of the doorway, a top Z strip 6 secured to the top 7 of said frame, and a door sill 8. Each of the Z strips will be understood to comprise two vertical flanges 9 and 10 that extend severally in two horizontally spaced, parallel vertical planes that parallel the plane of the doorway defined by frame 5, 5, 7. The outer and inner horizontally spaced flanges 9 and 10, respectively, in each Z strip are rigidly interconnected by a web 11. The flanges 10 of the two vertical strips 2, 2 and the horizontal strip 6 extend in common plane, up one jamb 5, along the top 7 of the door frame, and down the opposite jamb 5, providing a peripherally continuous seat against which the door 3 is adapted to seat along the margin of its inner surface, as indicated at 12 in Fig. 3. The webs 11 of the three Z strips 2, 6, 2 extend peripherally of the two side and top edges of the door 3 and receive such edges of the door in a relatively snug seam, as indicated at 13 in Fig. 3, while the bottom edge of the door fits upon the top surface of the sill 8, as shown in Fig. 1.

35 The three Z strips 2, 6, 2 are seated upon and secured to the outer faces of the doorway frame members 5, 7, 5, wood screws 15 serving for the purpose. It will be understood that the several Z strips are positioned and secured in such positions that the door-receiving opening formed by the webs 11 of the three strips and the sill 8 is of exactly the proper size snugly to receive the door.

40 In Fig. 3 it will be perceived that the edges 16 of the door 3 are not grooved; they are smooth and present no danger to the fingers of the user. But for the improvements of this invention, however, rain can work its way inwardly through the seam at the top of the door and drain downwardly over the inner surfaces 17 of the door, as mentioned in the introduction to this specification. The means for preventing this objectionable infiltration of water, comprise a small V-shaped gutter or trough portion 18 formed integrally with the Z strip 6 used at the top of the doorway. Advantageously, the trough is formed as a V-shaped element located adjacent to the lower edge of the outer vertical flange 9 of the Z strip 6.

45 More particularly, the bottom or bottom edge of the trough 18 is located substantially in a horizontal plane that extends through the corner formed by the merging of the vertical flange 9 with the horizontal web 11 of the Z strip 6. The trough 18 is such in form that it

50 may be formed integrally with the body of such Z strip in an aluminum-extruding operation. The V-shaped portion 18 lies outwardly beyond the seam 13 between the door and the web portion 11 of Z strip 6 (Fig. 3), and forms not only a shed or cover for such seam immediately below and within the portion 18, but provides a

55 channel which receives rain striking the doorway structure above the door and running downwardly toward the seam 13. As shown in the drawing, the strip 6 and its trough portion 18 extend not only entirely across the width of the door, but also across the upper ends of the size Z strips 2, 2, whereby the water collected in the trough portion is conducted to points beyond the vertical

edges of the door, whence the water can drain freely downward without objectionable consequences.

Fig. 4 illustrates the manner in which the top Z strip 6 is assembled, with the top of the right-hand Z strip, 2. The strip 6 and its trough portion overlie the upper end of the vertical Z strip. From this showing it will be understood that the opposite end of the Z strip 6 is similarly assembled, with the upper end of the left-hand Z strip 2. Fig. 5 shows how portions of the horizontal web, 11, and vertical, door-seat-forming, flange 10 are cut and removed at 19 and 20, respectively, to receive in nice fit the edges 21, 22, and 23 of the upper end of the side Z strip 2. And the flange portion 10 of the said strip 2 is cut away, as indicated, to match the end portion 24 of the flange 10 of the top Z strip 6. Thus, a very efficient, and inexpensive structure of extruded aluminum is provided to solve the problem described.

It may be noted that the V-shape form of the trough 18 is important, as it provides with the body of the Z strip, a section that may readily be extruded of aluminum, or other suitable light metal. And it is further important to observe that the outer face of the said trough 18 is flat, and parallels the outer face of the flange 9 with which it is integrally formed.

Within the terms of the appended claims various modifications will occur to the engineer, without departing from the spirit of the invention.

We claim:

1. A Z strip assembly to provide a seat in a doorway for an auxiliary door comprising two Z strips for each of the door jambs and a Z strip for the top of said doorway, each of said three strips comprising an extruded metal section having an outer flange, an inner flange, and a web interconnecting said flanges, the inner flanges of the three assembled strips extending in a vertical plane and the outer flanges extending in a vertical plane spaced from and parallel to the first-mentioned plane, with the interconnecting webs of the three assembled strips extending in continuity peripherally of the jambs and top of said doorway, and a longitudinally extending continuous trough portion formed integrally with and outstanding upon the outer flange of said top strip, the bottom of said trough portion being located substantially in a horizontal plane that extends through the corner formed by the merging of the outer, vertical flange with the web of said top strip and providing with such strip a section that may be integrally formed in a metal extruding operation, said top strip at its opposite ends overlying the upper ends of said jamb strips, whereby the ends of said trough portion on the top strip open laterally outward from the edges of a door mounted in said doorway and strip assembly.

2. A Z strip assembly to provide a seat in a doorway for an auxiliary door comprising two Z strips for each of the door jambs and a Z strip for the top of said doorway, each of said three strips comprising an extruded metal section having an outer flange, an inner flange, and a web interconnecting said flanges, the inner flanges of the three assembled strips extending in a vertical plane and the outer flanges extending in a vertical plane spaced from and parallel to the first-mentioned plane, with the interconnecting webs of the three assembled strips extending in continuity peripherally of the jambs and top of said doorway, and a longitudinally extending continuous trough portion formed integrally with and outstanding upon the outer flange of said top strip, the bottom of said trough portion being located substantially in a horizontal plane that extends through the corner formed by the merging of the outer, vertical flange with the web of said top strip and providing with such strip a section that may be integrally formed in a metal extruding operation, said top strip at its opposite ends overlying the upper ends of said jamb strips, whereby the ends of said trough portion on the top strip open laterally outward from the edges of a door mounted in said doorway and

strip assembly, the interconnecting web of said top strip being deleted at the ends of such strip through intervals substantially equal to the breadth of the outer flange of said jamb strips, to provide for the assembly of the outer flanges of said top and jamb strips in said first-mentioned vertical plane.

3. A Z strip assembly to provide a seat in a doorway for an auxiliary door comprising two Z strips for each of the door jambs and a Z strip for the top of said doorway, each of said three strips comprising an extruded metal section having an outer flange, an inner flange, and a web interconnecting said flanges, the inner flanges of the three assembled strips extending in a vertical plane and the outer flanges extending in a vertical plane spaced from and parallel to the first-mentioned plane, with the interconnecting webs of the three assembled strips extending in continuity peripherally of the jambs and top of said doorway, and a longitudinally extending continuous trough portion formed integrally with and outstanding upon the outer flange of said top strip, the bottom of said trough portion being located substantially in a horizontal plane that extends through the corner formed by the merging of the outer, vertical flange with the web of said top strip and providing with such strip a section that may be integrally formed in a metal extruding operation, said top strip at its opposite ends overlying the upper ends of said jamb strips, whereby the ends of said trough portion on the top strip open laterally outward from the edges of a door mounted in said doorway and strip assembly, the interconnecting web and the inner flange of said top strip being deleted at each end of such strip through intervals substantially equal to the breadth of the outer flanges of said jamb strips, to provide for the assembly of the outer flanges of said top and jamb strips in said first-mentioned vertical plane.

4. A horizontally extending Z strip for the tops of doorways comprising an extruded metal section having an outer flange positioned in a vertical plane, an inner flange parallel to and spaced from the outer flange, a horizontal web integrally connecting said flanges, said inner flange and said web forming a seat portion for a door, and a continuous horizontal trough portion formed on the outer face of said outer flange, the bottom of said trough portion being located substantially in a horizontal plane that extends through the corner formed by the merging of the outer, vertical flange with the web of said strip, said trough portion providing with the strip a section that may be integrally formed in an extruding operation.

5. A horizontally extending Z strip for the tops of doorways comprising an extruded metal section having an outer flange positioned in a vertical plane, an inner flange parallel to and spaced from the outer flange, a horizontal web integrally connecting said flanges, said inner flange and said web forming a seat portion for a door, and a continuous horizontal trough portion formed on the outer face of said outer flange, said trough portion being located substantially in a horizontal plane that extends through the corner formed by the merging of the outer, vertical flange with the web of said strip, said trough portion providing with the strip a section that may be integrally formed in an extruding operation, said trough portion having a plane outer face spaced from and parallel to the outer face of said outer flange.
